US00D701792S

(12) **United States Design Patent**
Kelleghan

(10) **Patent No.:** **US D701,792 S**
(45) **Date of Patent:** **** Apr. 1, 2014**

(54) **SIDE SQUEEZE BUCKLE WITH
INTEGRATED LED LIGHT**

(71) Applicant: **Bison Designs, LLC**, Longmont, CO (US)

(72) Inventor: **Brian James Kelleghan**, Longmont, CO (US)

(73) Assignee: **Bison Designs LLC**, Longmont, CO (US)

(**) Term: **14 Years**

(21) Appl. No.: **29/448,779**

(22) Filed: **Mar. 13, 2013**

(51) **LOC (10) Cl.** **02-07**

(52) **U.S. Cl.** **USPC D11/216**

(57) **CLAIM**

The ornamental design for a side squeeze buckle with integrated LED light, as shown and described.

DESCRIPTION

FIG. 1 is a front side elevation view of my new design for a side squeeze buckle with integrated LED light.

FIG. 2 is a back side elevation view of FIG. 1.

FIG. 3 is a right side elevation view of FIG. 1.

FIG. 4 left side elevation view of FIG. 1.

FIG. 5 is a top side plan view of FIG. 1.

FIG. 6 is a bottom side plan view of FIG. 1; and,

FIG. 7 is a front side isometric view of FIG. 1 with the side of the buckle separated, it being understood that all other surfaces are the same as those of the FIG. 1.

The features shown in broken lines in the drawing depict environmental subject matter only and form no part of the claimed design
